(57) **CLAIM**

I claim the ornamental design for a trailer fifth wheel lock puller, as shown and described.

DESCRIPTION

FIG. 1 is a perspective view of a trailer fifth wheel lock puller, showing my design;

FIG. 2 is right side elevation view;

FIG. 3 is a front elevation view;

FIG. 4 is a left side elevation view;

FIG. 5 is a rear elevation view;

FIG. 6 is a top view; and,

FIG. 7 is a bottom view.

The broken line portion of the figure drawings is included to show portions of the article that form no part of the claimed design.

1 Claim, 3 Drawing Sheets

FIG. 2

FIG. 3

FIG. 4

FIG. 5

FIG. 6

FIG. 7
